BROACH

James H. Gracey, Springfield, Mass.

Application February 28, 1946, Serial No. 650,936

3 Claims. (Cl. 29—95.1)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to an improved broach, more particularly to an improved broach for rifling firearm barrels.

In many firearm barrels, particularly pistol barrels, quick twist rifling is utilized to impart rapid rotation to the projectile. Likewise a large number of lands are utilized to insure adequate gripping of the projectile so that such projectile will not strip the lands. In rifling such a firearm barrel with a broach, such broach is required to perform a large amount of work to produce so many grooves with one pass thereof. Prior art broaching tools have not been very satisfactory when called upon to broach rifle a firearm barrel as above described.

Further, fabrication of prior art broaching tools utilized for one pass rifling of a firearm barrel having a large number of grooves was extremely difficult if the tool was constructed to cut all the grooves simultaneously. Such was due to the combination of the small diameter of such broaches and the large number of flutes which necessitated a longitudinal flute of extremely narrow width. This produced a broach having insufficient chip clearance resulting in inadequate lubrication and torn rifling unless the length of the broach was made excessive. Consequently it has been a practice to form broaching bits very long, with pairs of cutters spaced apart thereon a considerable distance, usually without any continuous helical fluting.

Accordingly, it is an object of this invention to provide an improved broach of moderate length for producing a large number of longitudinal grooves in a hollow workpiece, such as rifling in a firearm barrel, without undue loading of such broach.

Another object of this invention is to provide an improved broach having large width longitudinal helicoidal continuous flutes to facilitate fabrication of such broach and to provide improved chip clearance.

The specific nature of this invention as well as other objects and advantages thereof will clearly appear from a description of a preferred embodiment as shown in the accompanying drawings in which:

Fig. 1 is a side elevational view of the broach;

Fig. 2 is a fragmentary longitudinal section of one end of the broach illustrating the oil ducts;

2

Fig. 3 is a cross sectional view taken along line 3—3 of Fig. 1;

Fig. 4 is a cross sectional view taken along line 4—4 of Fig. 1;

Fig. 5 is a cross sectional view taken along line 5—5 of Fig. 1;

Fig. 6 is a cross sectional view taken along line 6—6 of Fig. 1;

Fig. 7 is an end view of the broach; and

Fig. 8 is a fragmentary planiform development of the helical fillets of the tool at the middle part thereof.

Briefly, this invention consists of a broach having a plurality of cutting portions which are virtually separate and complete gang tools, each having cutters for half the whole number of grooves to be cut, and spaced along the same shank. The cutting teeth of each successive portion are angularly displaced relative to the cutting teeth of the preceding portion. However each cutting portion has the same width chip clearance groove. In the case of a rifling broach having two cutting portions the cutting teeth of the second or rear cutting portion are so disposed that grooves cut by such portion will be spaced equidistantly between the grooves produced by the preceding cutting portion. A continuous flute joins the first portion with the second so that there is an unbroken channel, for ease in ejection of chips and oil along the length of the broach. Such result is accomplished by abruptly changing the twist of the chip clearance flute at approximately the mid-section of the total length of the broach. Thus a chip clearance flute is provided which is as many times wider than the flute of a conventional broach as the number of cutting portions.

The improved broach to be presently described herein is utilized for broach rifling firearm barrels. Such is only a specific illustration however, as this invention can readily be embodied in any broach utilized for producing longitudinally extending grooves in the bore of a hollow workpiece.

45 In Fig. 1 there is shown a rifling broach 20 fabricated in accordance with this invention. Such broach comprises two cutting portions 1 and 2 spaced along the broach and separated by an intermediate non-cutting portion 15 comprising fillets of reduced radius, each cutting portion 50 having substantially complete broaches but each having rows of cutting teeth equal to only one-half of the total number of grooves desired in the workpiece which will in this example be assumed to be eight. Each cutting portion 1 and

2 is provided with four longitudinal flutes 3 and intervening fillets, the latter being equally spaced with respect to one another. Flutes 3 and fillets are produced with a helical lead or twist corresponding to the twist of rifling desired in the firearm barrel. The flutes extend from the leading end of the tool the length of cutting portion 1, whereupon the gain or the lead of the flutes is abruptly increased for a short distance as shown at 4 in Fig. 1. At the end of portion 4 flutes 3 then assume the same lead or twist provided for portion 1 which continues to the end of portion 2.

Flutes 3 produce continuous fillets having top faces or lands 5 which extend the whole length of both portions 1 and 2. Obviously, lands 5 have the same twist as that of flutes 3. The abrupt change in lead of flutes 3 in portion 4 is provided to angularly displace lands 5 of cutting portions 1 and 2 relatively so that lands 5 of portion 2 are disposed equidistantly between lands 5 of portion 1.

Cutting teeth 6 are formed on the lands 5 of cutting portions 1 and 2 of broach 20 by cutting suitable transverse kerfs in the lands. Such teeth are of conventional construction and need not be further described herein. Lands 5 may be tapered in width throughout the length of cutting portions 1 and 2, such lands being narrower at the forward or entering end than at the rear or emerging end to facilitate drawing broach 20 through the bore of a firearm barrel (not shown). The portion 4 which joins cutting portions 1 and 2 is not provided with cutting teeth as shown in Fig. 1. Such portion is preferably of slightly reduced diameter so that such portion will not injure the bore.

On the left or forward end of portion 1, as shown in Fig. 1, there is provided a reduced diameter body end 7, and a terminal threaded tenon 8 so that broach 20 may be assembled to a broaching machine. Other conventional means than the one shown herein may be utilized for connecting the broach to such broaching machine. An axial duct 9 is provided in the forward end of broach 1 as shown in Fig. 1. Obliquely disposed holes 10 extending from duct 9 to the bottom of flutes 3 are provided to permit oil to flow into and along flutes 3 of broach 20 as shown in Fig. 1.

In the operation of this improved broach such tool is pulled through the firearm barrel (not shown) by the broaching machine (not shown) with the forward left end of cutting portion 1 entering the bore of the firearm barrel first. It is obvious to one skilled in the art that broach 20 must be drawn through the bore of the firearm barrel with a helical movement corresponding to the twist of lands 5 on broach 20. Lands 5 of portion 1 then cut corresponding grooves in the firearm barrel. When lands 5 of portion 2 enter the bore of the firearm barrel, new grooves are produced which are spaced equidistantly between the grooves produced by cutting portion 1. The chips removed by teeth 6 drop into flutes 3 where they are readily forced out by oil introduced under pressure to flutes 3 through holes 10 provided in the forward part of broach 20. As flutes 3 continue unbroken along the entire length of the broaching tool, such chips are readily washed out, thereby keeping the broaching tool clear and free to cut throughout its entire stroke.

From the foregoing description, it is readily apparent that there is hereby produced a broach that will easily produce a large number of grooves with one pass of such broach. Further, the

novel construction of this improved broach produces a much stronger broach so that the load placed thereon will not readily fracture such tool. In addition, the large continuous flutes 5 provided on this improved form of broach permit the chips produced by the cutting action of teeth 6 to be readily forced out, thereby substantially eliminating any bind or tearing due to the non-removal of such chips.

I claim:

1. A broaching tool for producing longitudinally extending grooves in the bore of a hollow workpiece comprising, a generally cylindrical body adapted to be insertable in the workpiece and having front and rear cutting portions formed thereon, a plurality of longitudinally extending rows of radial cutting teeth formed on said front cutting portion in equi-spaced relationship about the periphery thereof, each adjacent pair of said rows of cutting teeth defining a longitudinally extending chip clearance groove therebetween, and a plurality of longitudinally extending rows of cutting teeth formed on said rear cutting portion in equi-spaced relationship about the periphery thereof, each adjacent pair of said rows of cutting teeth on said rear cutting portion defining a longitudinally extending chip clearance groove therebetween, said rows of cutting teeth on said rear cutting portion being angularly spaced intermediate said rows of cutting teeth on said front cutting portion, said body having a plurality of grooves at the central portions thereof respectively connecting said chip clearance grooves in said front cutting portion with said chip clearance grooves in said rear cutting portion.

2. A broaching tool for producing longitudinally extending helical grooves in the bore of a firearm barrel comprising, a generally cylindrical body adapted to be insertable in the bore of the firearm barrel and having front and rear cutting portions formed thereon, a plurality of longitudinally extending helical rows of radial cutting teeth formed on said front cutting portion in equi-spaced relationship about the periphery thereof, each adjacent pair of said helical rows of cutting teeth on said rear cutting portion defining a longitudinally extending helical chip clearance groove therebetween, and a plurality of longitudinally extending helical rows of cutting teeth formed on said rear cutting portion in equi-spaced relationship about the periphery thereof, each adjacent pair of said helical rows of cutting teeth on said rear cutting portion defining a longitudinally extending helical chip clearance groove therebetween, said helical rows of cutting teeth on said rear cutting portion being angularly spaced intermediate said helical rows of cutting teeth on said front cutting portion, said helical rows of cutting teeth on said rear cutting portion having the same helical lead as said helical rows of cutting teeth on said front cutting portion, said body having a plurality of helical grooves of increased lead at the central portion thereof respectively connecting said helical chip clearance grooves in said front cutting portion with said helical chip clearance grooves in said rear cutting portion.

3. A broaching tool for producing longitudinally extending grooves in the bore of a hollow workpiece comprising, a generally cylindrical body adapted to be insertable in the workpiece and having a plurality of cutting portions formed thereon spaced along the body and separated by non-cutting portions, a plurality of longitudinally extending rows of radial cutting teeth formed on the foremost cutting portion in equi-

spaced relationship about the periphery thereof, each adjacent pair of said rows of cutting teeth defining a longitudinally extending chip clearance groove therebetween, and a plurality of longitudinally extending rows of cutting teeth formed on each following cutting portion in equi-spaced relationship about the periphery thereof, each adjacent pair of said rows of cutting teeth on each successive cutting portion defining a longitudinally extending chip clearance groove therebetween, said rows of cutting teeth on each successive cutting portion being angularly spaced intermediate said rows of cutting teeth on the preceding cutting portion, said body having a plurality of grooves at each of said non-cutting

portions thereof respectively connecting said chip clearance grooves in each of said cutting portions with said chip clearance grooves in the next following cutting portion.
